UNITED STATES PATENT OFFICE

LANE JOHNSON, OF INGRAM, PENNSYLVANIA, ASSIGNOR TO UNITED ENGINEERING & FOUNDRY COMPANY, OF PITTSBURGH, PENNSYLVANIA, A CORPORATION OF PENNSYLVANIA

REPEATER FOR ROLLING MILLS

Application filed March 20, 1928. Serial No. 263,098.

My invention relates to repeaters for rolling mills, such as rod and wire mills.

Repeaters are used on rolling mills to guide the front end of the rod or wire being rolled from one mill stand to another when the mill stands are set so that a loop can be formed in the rod or wire.

Repeaters, as heretofore constructed, have been limited to a definite spacing of roll grooves, and the flexibility of the mill was therefore quite limited. Inasmuch as the wearing-away of grooves on adjacent rolls is not constant, and since the life of such grooves, when run continuously, is a matter of a few hours, it is highly desirable that a repeater be capable of relatively quick adjustment between any possible lateral combination of grooves in adjacent rolls.

I provide a repeater that is adjustable for substantially all possible groove combinations on the rolls. It is adjustable, as a whole, in a direction substantially parallel to the axes of the rolls with which it cooperates for maintaining a definite span or space between the grooves in use. Slight variations in the span between different groove combinations are made by shifting one or more guides pivotally mounted at one or both ends of the repeater. Major adjustments between groove combinations are made by inserting sections of different lengths into the repeater. The repeater is made U-shaped, and such section is inserted in the base of the U.

By reason of the fact that rod or wire is frequently discharged from one set of rolls at a speed that is higher than the speed with which it is drawn into the succeeding rolls, due, in part, to its elongation in the rolls, loops of hot metal are formed, the lengths of which exceed the length of the path through the repeater. Consequently, a tendency exists for the material, if confined within the repeater, to buckle or tangle within the repeater.

To avoid such buckling or tangling in the repeater, I provide a portion of the repeater wall that is comparatively low and offset relative to the curve of the adjacent wall portions. Upon the formation of a loop in the repeater, the material moves into the offset

portion, and further buckling or tangling thereof causes it to snap or whip out of the repeater. When such a movement is once started, the escaping loop tends to enlarge itself and extends along and across the top of the repeater wall. The loop escapes from the removable section through a slot. The slot is overhung by a shield or apron that serves to hold and direct the material when an end is traversing the section, but the shield or apron does not interfere with the escape of the loop when an excess of material accumulates in the repeater and the whipping movement has been initiated. Provision is made for guiding the material, whether traversing the repeater or traveling in a loop outside of the repeater, to a guide for introducing it to the subsequent entrance rolls.

The accompanying drawings illustrate the present preferred embodiment of the invention, in which—

Figure 1 is a plan view of a repeater for a rolling mill embodying my invention;

Figure 2 is an end view of the closed end of the repeater;

Figure 3 is a side view thereof;

Figure 4 is an end view of one embodiment of the removable section of the repeater;

Figure 5 is an enlarged plan view of the section shown in Figure 4 illustrating its method of mounting;

Figure 6 is a plan view of a modified form of removable section;

Figures 7, 8 and 9 are sectional views of the removable section taken along the section lines VII—VII, VIII—VIII and IX—IX of Figure 5, respectively; and

Figure 10 is a fragmentary view of a pivotally mounted guide for the repeater ends.

Referring to Figures 1 to 3, a repeater 2 is disposed between exit rolls 4 and entrance rolls 5 in a rolling mill. The repeater 2 serves to guide material, such as rods and wire, discharged from the exit rolls 4 and introduce it to the entrance rolls 5. The rolls 4 and 5 may be of any commercial type and are illustrated in Figure 3 as being embodied in a three-high mill. Each of the

rolls is provided with a plurality of shaping grooves 6 mounted on the periphery thereof. The sizes of the grooves 6 may differ if it is desired to roll different sizes of material, or the grooves may all be of the same size as desired.

As the working life of any set of grooves 6 is a matter of hours, greater flexibility and efficiency of a mill is secured by providing the rolls with many grooves and also by providing means for adapting the repeater 2 to function with any possible combination of grooves between the rolls 4 and 5.

The rolls 4 and 5 are each provided with a stripping and guiding device 7 adjustably mounted on a cross bar 8 extending between stanchions 9 in the mill frame. The stripping and guiding devices 7 extend to the front edges of the mill frames 10, shown diagrammatically in Figures 1 and 3. The details of the rolls 4 or 5, the stripping devices 7 and the mills 10 may be of any preferred form, as they constitute no part of the present invention except in so far as they are necessary to complete the combinations herein-after described and claimed.

Rod or wire material discharged from the stripping device 7 cooperating with the exit rolls 4 enters a guide 11 having a groove 12 at the top thereof. The guide 11 is adjustably supported from a bed plate 13 by a frame 14. The guide 11 is secured to the frame 14 by bolts 15 anchored in intersecting slots 16, formed in flanges 17 on the guide 11, and slots 18, formed in a flange 19 on the adjacent repeater section. The flange 19 is secured by pins 20 to the frame 14. Limited adjustability of the guide 11 relative to the grooves 6 on the rolls 4 is obtained by adjusting the position of the bolts 15 in the slots 16 and 18, as shown by the dotted center lines in Figure 10. The frame 14 is movable along anchoring grooves 21 in the bed plate 13 by the manipulation of anchoring bolts 22.

From the guide 11 the material traverses a curved leg or section 23 of the repeater. The section 23 is curved through substantially 90 degrees for turning the material from the rolls 4 at substantially right angles to its direction when discharged from the rolls 4. The section 23 is supported at one end by its integral flange 19, and at the other end it is inserted into the next repeater section 24. The repeater sections 23 and 24 are directly secured together by a bolt 25 extending through ears 26 and 27 carried by the sections 23 and 24, respectively. The section 24 is secured by bolts 28 to a frame 29 which in turn is secured by anchoring bolts 30 to slots 31 formed in a bed plate 32, as shown in Fig. 7. Accordingly, the frame 29 is movable longitudinally of the bed plate 32. The inner edge of section 23 is open while the outer edge is provided

with a wall 34 having an outwardly offset portion 35 adjacent to the flange 19 for initiating a whipping or snapping movement of the material when escaping from the repeater. In the event that the material traversing the repeater tends to exert a back-pressure upon the wall 34, a loop starts to form in the portion 35, which loop escapes from the section at the offset portion 35.

Referring to Figures 5 to 9, inclusive, the section 24 tapers in the direction of movement of the material through the repeater. It is removable and constitutes the base of the U formed by the repeater. It is provided with a hood or apron 36 that extends upwardly and outwardly from the base thereof for confining and guiding the material while entering and initially traversing the section. The outer edge of the section 24 is provided with an inwardly tapered flange 37 that serves to overhang and confine rod or wire.

A slot 39 is provided between the upper edge of the flange 37 and the outer edge of the apron 36, through which the material 38 may escape, as hereinafter described. The small or discharge end of the section 24 overlies a forward edge of a curved repeater section 40.

The length of the section 24 may vary in accordance with the desired spacing between the sections 23 and 40 to conform to the combination of grooves 6 in use between the rolls 4 and 5. A section 24^a, shorter than the section 24, is shown in Fig. 6. A plurality of sections of different length are provided for rapid insertion between the sections 23 and 40 in accordance with desired changes in groove combinations during the operation of the mill.

The section 24 is secured to section 40 by a bolt 41, and by a bolt 42 extending between ears 44 and 45 formed on the sections 24 and 40, respectively. The section 40 is, in turn, supported by a frame 46 secured to a bed plate 47 by anchoring bolts 48. A bolt 49 extends through the section 40 and the frame 46. A bolt 50 also secures the section 40 to the frame 46.

The section 40 is provided with a continuous outer wall 51 and a bevelled portion 52 for guiding the material discharged from the section 24. The other end of the section 40 is supported by a flange 54 on a frame 55 and a bed plate 56. The construction of flange 54, frame 55 and bed plate 56, except as to height, are similar to those of the flange 19, frame 14 and bed plate 13, respectively.

A discharge guide 57 is adjustably mounted on the flange 54 by bolts 58 and slots 59, corresponding to the bolts 15 and slots 16 of guide 11, respectively. However, the mouth 60 of the guide 57 is relatively wide and extends on both sides of the wall 51 a sufficient distance to permit the material

to enter it from either the inside or the outside of the wall 51. The discharge end of the guide 57 cooperates with a stripping and guiding device 7 associated with the rolls 5. The repeater 2 is movable as a unit by loosening the bolts securing the several frame sections to the bed plates 13, 32 and 56, respectively.

Referring to Figure 3, the repeater is illustrated sloping upwardly for raising the material from a lower pass of the rolls 4 to an upper pass of the rolls 5, although it is to be understood that the elevation of the repeater may be modified as desired without departing from the scope of the invention.

When a loop of material escapes from the offset section 35, it tends to travel rapidly along the top of the wall 34 and through the slot 39 in the forward direction of material movement. This escaping movement is sufficient to snap or whip the material from the dotted line position in the repeater, and cause it to assume the dot and dash line position 65 shown in Figure 1. The material then enters the guide 57 through the mouth 60, externally of the wall 51 on the section 40.

Fending and bracing bars 62 are mounted at spaced intervals along the outer surface of the repeater for guiding material when looped outside of the repeater. The bars also fend the material 38 away from the bed plates and frames, thereby protecting them. The bolts 25 and 42 are utilized for supporting the bars 62, and additional securing devices 64 are provided at other points along the outer circumference of the repeater for the attachment of other guide rods. The outer ends of the rods 62 are permitted to rest on the ground.

While I have illustrated and described certain preferred embodiments of my invention, it is to be understood that various changes may be made in the invention without departing from the scope of the appended claims.

I claim:

1. In a repeater for a rolling mill, a plurality of sections for conducting material between sets of rolls, means permitting the escape of material from the sections, and inclined fending bars for protecting the sections from the escaped material.

2. In a repeater for a rolling mill, a plurality of relatively movable guiding sections, and a section insertible between said sections and having a hooded passageway with a slot formed therein for the escape of material traversing the repeater.

3. In a repeater for a rolling mill, a plurality of sections having ears formed thereon, means for supporting the sections, in a vertical direction, and bracing bars connected to certain of said ears and extending there-

from at an angle for supporting said sections in a horizontal direction.

4. The combination with a plurality of rolls each having a plurality of grooves, of a repeater comprising a body portion formed of sections adjustable relatively to each other and to said rolls and permitting the substitution of sections of different lengths to vary the span of the repeater, and conducting guides pivotally mounted for adjustment at each extremity of the body portion of the repeater.

5. In a repeater for a rolling mill, a conductor for directing material in a loop from one to another roll pass, the conductor being provided with an opening to permit the material to escape outwardly, and inclined fending means extending downwardly and outwardly from the conductor.

In testimony whereof I have hereunto set my hand.

LANE JOHNSON.
